APPARATUS FOR MIXING MATERIALS

William C. Anderson, San Francisco, Calif., assignor of one-half to William H. Brooks, Fairfax, Calif.

Application August 24, 1936, Serial No. 97,492

3 Claims. (Cl. 259—82)

This invention relates to an apparatus for mixing materials, and especially to an apparatus whereby crushed or pulverized materials of different character may be thoroughly mixed or 5 blended, or semi-liquid or plastic and also liquid materials may be blended.

The object of the present invention is generally to improve and simplify the operation of mixing crushed or pulverized materials, either dry or wet, 10 and similarly plastic, semi-liquid and liquid substances, and particularly to provide a method and apparatus whereby the mixing or blending of materials, whether dry, plastic, semi-liquid or liquid, is accomplished by repeated successive 15 spreading and gathering operations accompanied by the simultaneous screening of the materials and tumbling of the materials over and over upon themselves.

One form of apparatus which is employed is 20 shown by way of illustration in the accompanying drawing, in which—

Fig. 1 is a central, vertical, longitudinal section through the mixing apparatus;

Fig. 2 is a cross section taken on line II—II of 25 Fig. 1;

Fig. 3 is a perspective view of the removable frame containing the screens;

Fig. 4 is a diagrammatic view showing the gathering action of one screen;

Fig. 5 is a diagrammatic view showing the spreading action of another screen;

Fig. 6 shows a modified form of screen arrangement.

Referring to the drawing in detail, and particularly Figs. 1 and 2, A indicates in general a horizontally disposed elongated cylindrical-shaped container, which is permanently closed at one end by a head 2 and provided with a removable head 3 in the opposite end. The cylinder or container 40 is supported to permit rotation upon its central longitudinal axis; a shaft 4 journaled in the bearing 5 forming a support at one end and an annular track ring 6 engaging roller 7 forming a support for the opposite end. Any suitable means 45 may be provided for rotating the drum, such as a gear, or pulley 8, secured on the shaft 4.

The container is provided with a cover 9 which may be opened when materials are to be emptied or discharged, and means are placed within the 50 container for mixing or blending materials; the mixing means employed being best illustrated in Figs. 2 and 3.

The mixing mechanism consists of a pair of ring-shaped end members, indicated at 10 and 11, 55 which are connected by longitudinally extending

bars 12; the rings and bars forming a frame generally indicated at B, which supports a pair of members 14 and 15 which serve several functions, first, that of elevating and dropping the materials to be mixed; secondly, that of alternately gathering and then spreading the materials; and third, that of subjecting the materials to a screening action.

When dry or pulverized materials are to be mixed or blended, the members 14 and 15 are formed of a screen material of suitable mesh. In other instances they may be perforated plates and where liquids are to be blended unperforated plates may be employed. Be that as it may, one essential feature of the present invention is that the members 14 and 15 must present angular or inclined faces, such as shown at 14^a and 15^a, this being of great importance as it is the angular disposition of these members that causes the materials to be alternately spread and gathered during rotation of the container.

Another desirable feature is the offsetting of the members 14 and 15 with relation to each other, as shown in Fig. 2. That is, they are placed parallel to a radial line 16 drawn across the cylindrical-shaped container and on opposite sides thereof. This offsetting of the members 14 and 15 causes transfer or dropping of the material from one member to the other once during each half revolution of the container and is of considerable importance as it materially facilitates screening of the materials when that is desired.

For the purpose of permitting cleaning of the mixer and also to permit changing of the screens 35 14 and 15, for instance from one mesh to another, the frame B supporting them is made removable. This is accomplished as follows: Secured within the inner face of the cylinder, or container A, are a series of channel-shaped tracks 17. Journaled at the opposite ends of the bars 12 of the frame B are rollers 18. The frame B containing the screens or members 14 and 15 may be slipped endwise into container A when the end cover 3 is removed. The rollers 18 will then enter between 40 the channel members 17 and will not only support the frame centrally within the container but a driving connection will at the same time be formed between the container and the frame, as the rollers 18 enter the channel 17 and are secured 45 against lateral movement with relation thereto; endwise removal of the frame when once inserted being prevented by applying and securing the cover 3 by bolts and nuts or any other suitable means. Hence, by merely removing the cover 3, 50 55

the frame B as a whole may be readily removed in an endwise direction for cleaning, inspection and repair, or to permit changing of the screens or members 14 and 15.

- 5 5. In actual operation, if dry pulverized materials of different character are to be thoroughly mixed or blended, they are placed within the container by merely opening the cover 9. When the different materials have been entered, the cover 10 is closed and power is applied to rotate the container, the revolutions of the container being comparatively slow. During each rotation of the container, the screens will tend to pick up the material and elevate it and when the 15 screens assume the position shown in Fig. 2, the material that is not sifted through the uppermost screen will slide off and drop onto the lower screen; this being important as such movement materially facilitates screening and 20 mixing of the material. Also, it will be obvious that as the cylinder rotates and the material is being sifted through the screens it will roll or tumble over and over upon itself and thus produce a further mixing action.
- 25 5. One or more important features accomplished is that of alternately spreading and gathering the material as it is being mixed. This is accomplished as follows: By inclining the screens, as shown in Fig. 3, one screen will assume the 30 position shown in Fig. 4 and any material picked up by that screen and elevated will naturally tend to gather towards the center of the screen and sift through. When the next screen picks up the material and elevates it, it will assume 35 a reverse position, as shown in Fig. 5, and in this position the material will tend to slide down the inclined surfaces of the screen towards the opposite ends of the drum and thus spread the material. The first mentioned screen will, during 40 the next revolution, pick up the spread material and as its sides are disposed on opposite or downwardly inclining angles the material will tend to slide down the center of the screen there to be gathered towards the center of the container. This operation will, of course, be repeated over and over during the rotation of the 45 drum and thorough mixing or blending of the materials is insured.

50 One important use for dry mixing is in connection with the baking industry where different ingredients must be thoroughly mixed.

In the paint industry where a semi-liquid substance is to be handled, partially perforated plates may be employed as a substitute for the 55 screens.

In other industries where purely liquid substances are to be mixed, unperforated plates may be employed, but in each instance the angular position of the plates or screens should be 60 such that the screens cooperate to first gather and then to spread the material, whether it be

in the pulverized dry form, or it be in a plastic semi-liquid or liquid form.

These screens, or in other words the members 14 and 15, when arranged as shown in Fig. 3 will spread and gather the material once during each revolution. By placing the screens as shown in Fig. 6, the material will be gathered and spread twice during each revolution. Either arrangement is efficient but the choice in the arrangement will obviously depend upon the materials 10 being handled.

While certain features of the present invention are more or less specifically described, I wish it understood that various changes may be resorted to within the scope of the appended claims. 15 Similarly, that the materials and finish of the several parts employed may be such as the manufacturer may decide, or varying conditions or uses may demand.

Having thus described my invention, what I 20 claim and desire to secure by Letters Patent is:—

1. An apparatus of the character described comprising a cylindrical-shaped horizontally disposed container, means for supporting and rotating the container, said container adapted to receive a plurality of materials to be mixed, and a pair of screens secured within the container, said screens being V-shaped longitudinally and said screens alternately elevating and dropping the material and simultaneously alternately spreading and gathering the material during 25 rotation of the container.

2. An apparatus of the character described comprising a cylindrical-shaped horizontally disposed container, means for supporting and rotating the container, said container adapted to receive a plurality of materials to be mixed, a detachable head on one end of the container, a frame within the container and endwise removable therefrom, means within the container for receiving, supporting and rotating the frame, and a pair of screens secured in the frame, said screens having angularly disposed surfaces, said screens alternately elevating and dropping the materials and simultaneously and alternately 40 spreading and gathering the materials during 45 rotation of the container and the frame.

3. An apparatus of the character described comprising a cylindrical-shaped horizontally disposed container, means for supporting and rotating the container, said container adapted to receive a plurality of materials to be mixed, and a pair of screens secured within the container, said screens presenting surfaces which incline longitudinally from the ends towards their 50 centers so as to present inclined surfaces, and said screens alternately elevating and dropping the materials and simultaneously spreading and gathering the materials during rotation of the 55 container.

60 WILLIAM C. ANDERSON.
